UNITED STATES PATENT OFFICE

ORMOND R. BEAN, OF PORTLAND, OREGON

UNITARY COMBINED TUB AND SURGICAL BASIN

Application filed May 25, 1927. Serial No. 194,098.

My invention relates to sink fixtures designed for use in athletic training quarters, and in surgical treatments.

As well known, the treatment of bruised, strained feet, ankles, legs, and knees, commonly consists in the application of hot or cold packs, or towels, placed upon the injured member; these packs or towels being heated or cooled by immersion, or soaking in hot or cold water.

Heretofore, because of inadequate equipment, such treatment required an attendant, and was a very inconvenient and sloppy procedure; and, in consequence, constituted more or less of an unavoidable nuisance in all athletic training quarters.

The principal object of my invention is to provide a relative inexpensive compact combined tub and surgical basin especially adapted for administering the self-treatment of the bruises and sprains above referred to.

I attain my object in a unitary fixture comprising an intermediate main basin section and supplemental basins of materially less vertical dimension than that of the main basin, the end walls of the main basin terminating below the upper edges of the side walls to provide overflow communications between the respective basins and the upper portion of one of the side walls being adapted to constitute a seat and drain common to all basins with independent drainage outlets for each basin.

Thus the patient with my fixture may sit with his feet in the foot tub and himself apply the wet packs, conveniently, to his arms, legs, or feet, as desired, and the water draining off the packs will drip in the fixture and be carried off through the sewer pipe connection.

Further particulars and other features and the details of construction of my invention, and its use in practice are hereinafter fully described with reference to the accompanying drawings.

In the drawings:

Fig. 1 shows a perspective view of my invention looking at the front thereof;

Fig. 2 shows a section taken on the line 2-2 of Fig. 1, and illustrates details of construction;

Fig. 3 shows a section taken on the line 3-3 of Fig 1.

My invention preferably consists of a one piece casting of metal or concrete *a* and comprises an intermediate basin section *b* having side walls *c*, *d* and end walls *e*, *f*, bottom *g*. The side walls have longitudinal extensions *h*, *h'*, *i*, *i'* in both directions beyond the main basin *b*, such extensions are provided with end walls *j*, *k* and bottoms *l*, *m* to form in each direction, beyond the main basin, supplementary basins as *n*, *o* of materially less vertical dimensions than that of the main basin; so that such supplementary basins will require a materially less volume of water and will serve to emerge therein bandages, and will be further convenient for the treatment of the arms and hands.

The end walls *e*, *f* of the main basin extend above the bottom of the supplementary basins but terminate below the upper edges of the side walls *c*, *d*, as shown by *e'*, *f'*, so as to provide overflow communications between the respective basins, especially between the supplementary basins and the main basins. The upper portion of the front side wall *c* is sloped outwardly and upwardly through its full length, as shown by *p*, to provide a seat constituting also a downwardly inclined drain common to all basins. Each of the basins is provided with an independent drainage outlet as indicated by *q*, *r* and *s*, such outlets of convenience connected by pipes *t* to a common outlet *u*, and a water service fixture *v* is adapted to fill either of the basins with water at the desired temperature.

I claim:

A unitary combined tub and surgical basin, comprising an intermediate main basin section comprising side walls, end walls and a bottom, the side walls being extended in both directions beyond the main basin section with the lower edges of such extensions materially above the bottom of the main basin, end walls and bottoms connecting the extended portions of the side walls to form in each direction beyond the main basin supplemental basins of materially less vertical dimension than that of the main basin extending above the bottoms of said supplemental basins but, the

- end walls of the main basin terminating below the upper edges of the side walls to provide overflow communication between the respective basins, the upper portion of one of the side walls being outwardly and upwardly sloped throughout its full length to provide a seat and downwardly inclined drain common to all basins, and an independent drainage outlet for each basin.

ORMOND R. BEAN.
